BOOKBINDING MEANS

Robert Alonzo Williams, Chicago, Ill.

Application June 16, 1936, Serial No. 85,471

16 Claims. (Cl. 281—25)

This invention relates to bookbinding means, and has for a particular object the provision of a means applicable to the art of edition bookbinding.

5 The invention resides in the novel combination and form of parts, to be hereinafter particularly described in view of the annexed drawing in which:

Fig. 1 is a perspective view of a complete book 10 bound in edition style;

Fig. 2 is a vertical section taken along the lines 2—2 of Fig. 1;

Fig. 3 is an enlarged sectional detail taken along the lines 3—3 of Fig. 2;

15 Fig. 4 is an enlarged fragmentary section taken along the lines 4—4 of Fig. 2, while

Fig. 5 is an exploded perspective view of the book of Fig. 1.

The present invention is directed particularly 20 to the art of edition bookbinding and is adapted to simplify the heretofore elaborate and expensive methods peculiar to this art, with a particular view to eliminating certain of the more complicated and expensive steps necessary in the methods of modern edition bookbinding, and at the same time to provide a binding which is superior 25 to any heretofore known in the matter of simplicity and ruggedness and novel structural features.

30 Referring to Fig. 5, the method contemplates the preliminary steps of cutting and folding a plurality of printed sheets into folded groups or signatures 10 and gathering these into an initial bookform or outline, each signature being itself 35 in the nature of a small unbound sheaf or book, and the group of signatures being preferably gathered in the form shown, and stapled as by the wire staple 12, shown in Fig. 2, to facilitate the handling of the gathered signatures in the 40 succeeding steps of the method. These cutting, gathering and folding operations are usually accomplished by automatic machine means well-known in the art.

When the signatures are gathered in book form 45 and stapled for handling they are provided with a lateral key or wedge slot 11 (Figs. 2 and 5) adjacent the rear longitudinal extremities of the signature folds, and these slots are directed substantially toward the center of the book form and 50 individual signatures thereof at an angle preferably of 45 degrees relative to the lateral axes of the sheets or signatures. The formed signatures are then represented in the completed step generally indicated at "A" in Fig. 5.

55 Subsequently a pair of cover boards 14 having

suitably beveled rear longitudinal edges 14' are joined by a flexible hinge member 16 which may be of fabric or the like and which is preferably glued by methods also well-known in the art to the inner sides of the cover boards 14 in the region thereof adjacent the said longitudinal beveled edges 14'.

The hinge member 16 may then be provided with a lateral key slot 11' corresponding to the key slot 11 in the formed signatures above described, or the slot 11' may have been previously applied to the hinge strips, as desired.

In this condition the assembled covers 14 joined by the hinge 16 will form what is termed a "Casing" represented by the step generally indicated 15 at B in Fig. 5.

The casing B may then be fitted upon the book form A so that the respective key slots 11 and 11' are registered, whereupon a key member or wedge 20, the form of which will be hereinafter 20 particularly described, is inserted in the registered slots 11 and 11' in such manner that the lower key surface 22 thereof rests snugly within the said slots (see Fig. 2 particularly). This step of the procedure is generally indicated at C in 25 Fig. 5.

At this juncture the paper end sheets 18, being the outer leaves of the outermost signatures or sections 10, may be suitably glued to the inner or back sides of each of the respective covers 14, 30 so as to cover the entire inner surfaces thereof and particularly the juncture of the hinge member 16 with the said cover boards (see Figs. 2 and 3 particularly).

35 Thereafter a rigid backbone member or backbone channel 34, a preferred form and construction of which will be hereinafter particularly described, is fitted upon the combined casing and book form so that its free longitudinal edges 36 in sidewalls 35 thereof substantially confront the rear longitudinally extensive beveled edges 14' of the cover 14. This step being generally represented at D in Fig. 5, the result of which is shown in assembled form in Figs. 2 and 3 particularly.

40 By the foregoing method of binding a number of heretofore necessary steps peculiar to the art of edition bookbinding are eliminated, as those skilled in the art will readily recognize. In particular, the necessity for sewing the signatures together in any of the several recognized manners is eliminated, as is also the heretofore essential step of gluing-up of the signatures for rounding and backing. In addition, the present 45 method makes unnecessary the heretofore re- 50

quired step of "casing-in" which included gluing the signatures into the cover.

By the elimination of the foregoing particularly specified steps which are recognized as essential in the art of edition bookbinding as heretofore practiced, I have correspondingly eliminated the need for certain expensive machinery and handling operations involved in these previous methods, and, while I am aware that other methods have been proposed for the elimination of certain of the foregoing steps, the method here presented provides an edition bound book which is superior in the matters of simplicity and ruggedness to anything thus far developed, as will appear from the following particular description of the novel keying and channeling members used in my above described method.

A preferred form of a keying or wedging member 20 for use in the above described bookbinding method is desirably constructed of metal and has a vertical wall 21 with an angularly disposed keying or locking surface 22 and opposite side wings 24 and 25 (Fig. 5). This member 20 may conveniently be struck from a suitable die in large numbers for use in the binding operation.

The backing channel 34 is also preferably made of metal and has opposite side walls 35 corresponding generally in their lateral width to the width of portions 24 and 25 of the key member 20 and is so dimensioned that the said key member may be slidably fitted therein with its vertical wall 21 confronting the bottom portion of the channel 34, the wing portions 24 and 25 sliding against the walls 35 of the channel member.

In placing the backing channel 34 upon the cased book in conformance with step D of Fig. 5, the channel member may be slid longitudinally upon the hinge portion of the cased signatures after the keying members 20 have been applied thereto in the manner indicated in the dotted line representation of Fig. 1. Or, if desired, the channel member 34 may be pressed or formed directly upon the said hinge portion of the cased signatures after the keys have been inserted, and for this purpose the side walls 35 of the channel member may be spread apart slightly to facilitate such application and thereafter the said side walls 35 may be pressed or crimped to compressably grip the fold portions of the signatures, together with the hinge portion of the casing, and thus rigidly secure the several members, indicated in the steps A to D, in Fig. 5, in the assembled relation shown in Fig. 1.

In either of the above alternative methods of applying the channel backing to the cased signatures, the free longitudinal edges of the side walls 35 of the channel 34 are bent back upon themselves to provide the lip portions 38, which are adapted to confront the free longitudinal edges 24' and 25' of the wings 24 and 25 of the key member 20, and in this manner the said key member is secured for slidable longitudinal movement in the channel member 34, but will resist any displacement laterally of the channel.

In like manner, the lateral edges of the side walls 35 of the channel member 34 are bent back upon themselves to form lip portions 39 which are adapted to confront the lateral edge portions 29 of the key member 20, when the latter is secured in the channel, and are adapted to limit the longitudinal movement of said key members therein. It will thus be apparent that with either of the alternative methods of applying the backing channel to the cased signatures with the key member in place, that is to say by sliding the

channel in a longitudinal direction upon the casing, as indicated in Fig. 1, or by placing the channel squarely upon the cased signatures and thereafter crimping it into place, the said key member will be securely engaged and its movement therein limited in the particular manner set forth. However, should the sliding method of applying the channel member be used, it will be apparent that the lateral edge extremities of the channel side walls 35, which form the lips 39, will necessarily be left in their originally extended condition, as indicated by the dotted line representation in the upper part of Fig. 2, and after the channel has been thus applied the said edge portions may be pressed into place to form the lips 39, as shown in Fig. 5.

By the use of my improved method and binding means, books, and particularly those in edition form, are very ruggedly bound with particular respect to the securing of the signature sections against movement in any direction relative to one another, or their backing or casing, and also from tearing-out of folds or leaves of the individual sheets comprising the signatures, and other deformations to which edition-bound books manufactured by previous methods are commonly subject.

It is also important to observe that my novel binding permits the use of covers of any weight, and that whereas the covers provided in methods heretofore used were secured to the formed signatures largely through the medium of the end sheets, the covers in my present construction are supported entirely by the hinge member 16, which may be attached to the cover members as securely as the circumstances may warrant, the hinge member being held in assembled relation to the signatures by the conjoint action of the keying members 20 over limited surface areas thereof, and the compressing and binding action of the channel member over its entire areas.

Attention is also called to the fact that the keying member, once it is inserted in the key slots, can move in only one direction, namely, out of the said slots at the particular angle at which they are pitched; and that movement in any other direction is entirely prevented, for the locking action of the key member increases in substantially direct proportion to the displacing stress which is put upon it. When the channel member has been assembled with the key member, the latter is incapable of displacement in a direction to remove it from the key slots since the companion key member, being pitched oppositely to the first key member, prevents any pivotal movement of the channel member, which would be necessary to move the other key member of the pair out of its slot. The resulting binding structure is therefore extremely rugged and makes possible the production of edition books which will withstand a very high degree of abuse; and this advantage, together with others already pointed out, distinguishes the invention as a decided advance in the art of edition bookbinding.

It will be understood that the number of keys or wedges which may be applied to a given book in the practice of this method is not restricted to two. In heavier books, for example, it may be necessary or desirable to apply multiple wedges 20, and where this is done, I prefer to cut a pair of key slots 11' at a distance from the middle line of the signature form, and on either side of the staple 12 (Fig. 2), and these latter slots 11' are also preferably pitched at an angle of less than 90 degrees relative to the lateral axis of the grouped

signatures, the longitudinal axis, of course, being that parallel to the folded edges of the signatures 18. But, whereas the endmost wedges 20 are pitched convergently toward the center of the book or the center of the plane of the several sheets of the signatures, and thus toward each other, I prefer to slant the inner pair of wedges 20' away from the said center of the book form and in a convergent direction relative to their respective endmost keys or wedges 20. Hinge slots 11", cut in the cover hinge 16, where keys 20' are used as indicated in Fig. 2, are correspondingly slanted.

I also find it convenient in the practice of this method where the aforementioned diverging central key slots are employed, to form the central wedge 20' with integral key surfaces 22', and thus expedite the manufacture of the wedges or keys as well as the method by which the book is bound in edition style.

It should further be explained that my method, where it refers to casing-in and the casing represented in step B of Fig. 5, refers to the generally used term by which the step of providing the book form with a cover, is known to those familiar with the art of edition bookbinding. And in this regard, I desire to point out that I do not intend to be restricted to the form of casing shown in Fig. 5, step B, wherein the cover boards 14 have a rear longitudinal beveled edge 14' and are joined by a cloth or the like hinge strip 16.

The casing to be used in step B of Fig. 5 may be of the full-cloth cover type in which the cover boards have no rear beveled edge 14', and the cloth 16 is extended entirely over the cover boards in such manner that they are completely encased in cloth and preferably have a double thickness of cloth or fabric over the hinge portion, one facing the outer most side of the hinge part (16) and the other, facing the innermost side of this hinge part.

Where the type of casing just above described is used, the sliding method of applying the channel or backbone member 34 as indicated in the dotted lines of Figs. 1 and 2, is particularly convenient, and it will be apparent that when the full-cloth covers such as described are used, the juncture between the hinge part and the cover boards, which is visible in the endwise section of Fig. 3, is less pronounced, since there will be another thickness of cloth passing from the topmost surface of the cover (and also the bottommost) under the side wall 35 of the channel 34.

Summarily, the heretofore commonly practiced methods of binding books in edition style have required the sizing, folding and gathering of sheets into signatures; sewing or stitching the signatures; gluing-up the signatures for rounding and backing; rounding and backing the signatures; gluing a lining cloth on the backbone of the signatures; gluing the lining (or hinge) cloth onto cover boards to form a case or cover; and finally casing-in by gluing the end sheets of the signatures onto the inside surfaces of the case or covers.

In accordance with the present invention, the binding of a book in edition style is accomplished by the following steps:

- (A) Forming the book sheets in signatures; gathering the signatures in an elementary book form; slotting the backbone of the signatures;
- (B) Applying a casing to the gathered signatures;
- (C) Keying the said casing and signatures together;
- (D) And compressibly securing said keyed cas-

ing and signatures with a substantially rigid backbone member.

While I have described a preferred means in characterizing my invention for purposes of illustration, it will be apparent to those skilled in the art that the invention is susceptible to modification without departing from the spirit of the invention, and I therefore do not wish to be restricted to the precise details recited, but desire to avail myself of all the modifications and variations coming within the scope of the following claims:

Having thus described my invention, what I claim and particularly desire to protect by Letters Patent of the United States is:

1. A book comprising a plurality of gathered signatures having lateral slots cut at an oblique angle in the hinge portions thereof, a cover for said book including a pair of cover boards hingedly joined and having openings in the hinge part thereof in registration with said slots in said signatures, a plurality of key members each having an obliquely disposed key part inserted in said registered slots and a longitudinally extensive channel member fitted upon the said signatures and hinged part of said covers and having parts grippingly engaging the aforesaid signatures and cover members and the said key members in assembled relation.

2. A book comprising a plurality of folded sheets gathered in groups with their fold portions in superposed relation and having lateral slots cut into said sheets across the fold portions thereof at an oblique angle relative to the long axes of the fold edges of said sheets; a cover member including cover boards hingedly joined and having a cut-away portion in registration with the said slots in said folded sheets; a plurality of key members each having a bottom wall and a pair of oppositely disposed side walls with a key part extended between the said side walls at an oblique angle to the said bottom wall, said key members being fitted upon said folded sheets and cover members in assembled relation so that the said key parts are fitted into the said registered slots with the said bottom walls thereof fitted substantially against the folded edges of said sheets and the hinge part of said covers thereon; and a binding member in the form of a longitudinally extensive channel piece having bottom and side walls and fitted onto the said folded sheets and cover member with the bottom wall thereof in confrontation with the said bottom wall of said key members and the said hinge member, and having its side walls clamped upon the said hinge member and sheets therein in the region adjoining the said fold parts, the edge extremities of the said bottom and side walls of said channel member being bent back upon themselves to form lip parts for limiting the movement of said key members.

3. A book comprising a plurality of gathered sheets having a plurality of lateral slots cut obliquely into an edge thereof, a plurality of U-shaped keying clamps fitted upon said edge, said clamps each having a keying tongue extended obliquely from the bottom thereof and into a said slot, and a U-shaped backbone member fitted upon said edge and the clamps thereon with its side portions firmly clamped upon the outermost ones of said sheets in the region adjoining said edge thereof, said backbone having parts along its edge portions for retaining said clamps therein.

4. A book comprising a group of superposed

sheets having registered lateral slots cut obliquely into the sheets along one edge thereof, and binding means including locking keys in the form of members having a back surface fitted 5 against the slotted edge of said group of sheets and each said member having a keying tongue part extended into one of said slots and having side surfaces overlying the outermost sides of the group of sheets in the region adjacent said 10 edge, said means further including a grooved member having a bottom surface fitted upon the slotted edge of said group of sheets and the key members thereon and having a pair of opposite side surfaces extended from the said bottom surface thereof and clamped upon the outermost sides of the group of sheets adjoining said slotted edge and upon the said side surfaces of said locking key members, said grooved member having parts securing said locking key members 15 20 against withdrawal therefrom.

5. A book comprising a group of superposed sheets having a plurality of registered, lateral slots cut obliquely into one edge of the group, and a longitudinally grooved backbone fitted 25 upon said edge and having a plurality of locking keys in the grooved part of the backbone, each of said locking keys having a part extended in a direction obliquely away from said backbone toward and into one of said slots, said backbone 30 having parts turned back upon itself toward the grooved part thereof to prevent the withdrawal of said locking keys therefrom.

6. Binding means for leaf matter arranged in a stack, said means including a longitudinally 35 channeled backbone fitted onto an edge of the stack and a plurality of recessed key members secured in said backbone against movement laterally out of the same and each fitted around said edge of the stack and having an oblique lateral tongue extending into an oblique lateral slot formed in said edge, there being one of said key members positioned near each of the ends of said stack edge, and said backbone having endwise parts engageable with said key members near the ends of the stack edge as aforesaid to 40 prevent longitudinal movement of the backbone 45 on said edge.

7. A folio device including a stack of leaves having a binding edge provided with a plurality 50 of lateral oppositely inclined oblique slots cut therein, there being one of said slots near each of the ends of said binding edge, a plurality of locking keys fitted around said edge and each having an oblique tongue extended into one of said slots, together with an elongated channel-shaped backbone fitted onto said binding edge and the keys thereon and having its longitudinal side portions closely overlying the side portions of said stack adjoining said binding edge, said 55 backbone further having its free edge portions turned inwardly toward adjacent underlying portions of said key members and preventing separation of the latter from the backbone and further preventing longitudinal movement of the 60 backbone on said edge.

65 8. A book comprising a stack of leaves having a binding edge provided with a plurality of lateral slots cut obliquely into the stack, a plurality of locking keys fitted around said edge and each having an oblique tongue extending into one of said slots, and an elongated backbone strip fitted around said binding edge and the keys thereon and having free edge portions bent in a direction against said keys and preventing 70 separation of the latter from the backbone in a 75

lateral sense and further preventing longitudinal movement of the backbone relative to said edge.

9. A book comprising a stack of leaves having a binding edge provided with a plurality of lateral slots cut obliquely into the stack in a direction away from said edge, a plurality of keying members each having a bottom and adjoining opposite side portions and fitted onto and around said binding edge, each of said keying members further having a tongue portion extended obliquely up from the bottom thereof between said side portions and extending into one of said slots, together with an elongated channel-like binding strip fitted onto and around said binding edge 10 of the stack and the keying members thereon 15 and having free edge portions bent back upon itself toward said binding edge and preventing separation of said keying members laterally therefrom, and said binding strip having means at its ends preventing movement of said keying 20 members longitudinally out of the same.

10. A book comprising a stack of leaves having a binding edge provided with a plurality of lateral slots cut obliquely into the stack in a direction away from said edge, there being one 25 of said slots near each end of said edge and each of the latter slots being obliquely inclined oppositely to the other, a plurality of key members each having a bottom and adjoining opposite side portions and fitted onto said binding edge and each further having an integral, rigid tongue extended obliquely up from an end of said bottom between said side portions and said tongues each being engaged in one of said slots, together 30 with an elongated channel-shaped binding strip 35 fitted onto said binding edge and the key members thereon and having rims formed along its free edge portions and preventing lateral separation of the same and said key members and also effective in cooperation with the said key members disposed near the ends of said binding edge 40 to prevent longitudinal movement of the binding strip relative to said edge.

11. A book comprising a stack of leaves having a binding edge provided with a plurality of 45 lateral slots cut obliquely into the stack in a direction away from said edge, at least two of said slots being oppositely inclined in an oblique sense, a plurality of locking wedges each shaped to fit around said edge and each having a rigid 50 integral and obliquely extending tongue, said wedges being fitted onto said binding edge with their respective tongues in one of said slots, and an elongated channel-shaped backbone fitted onto said binding edge and the wedges thereon 55 and having longitudinal sidewall portions closely overlying the side portions of said stack adjoining said edge, said backbone further having means arranged along its free edge portions preventing both lateral and longitudinal displacement of said backbone relative to said wedges 60 and said binding edge.

12. A book comprising gathered leaves having a binding edge with a plurality of oblique lateral slots cut therein, a plurality of keys of substantially channel-like cross section fitted onto said binding edge of the stack and each having rigid oblique tongue portions extending into one of said slots, together with an elongated backbone fitted over said binding edge and the keys thereon 65 and having longitudinally extensive groove formations along its opposite sides and fitting over the underlying edge parts of said keys, said backbone also having means at its ends engaging the outermost ones of said keys and preventing move- 70 75

ment of the backbone in a longitudinal direction on said binding edge.

13. Binding means for a stack of leaf matter and including an elongated channel member having therein a plurality of channel-shaped keys adapted to move longitudinally in said channel member, and the latter having parts along its longitudinal free edge portions effective to prevent movement of said keys laterally out of the same, said channel member and the keys therein being fitted over an edge of said stack, each of said keys having a lateral tongue extending obliquely therefrom into said stack and at least two of said tongues being inclined oppositely to each other in an oblique sense, said channel member having means engaging said keys nearest the longitudinal ends of said binding edge to prevent longitudinal movement of the channel relative to said last-mentioned keys and said edge.

20 14. Binding means for a stack of leaf matter and including an elongated channel-shaped member provided with longitudinally extensive grooves on opposite sides thereof, and a plurality of locking keys in said member and each having opposite longitudinal side portions engaged in said grooves in a manner to permit longitudinal sliding movement of the keys in said member and effective to prevent movement of the keys laterally out of the same, the channel-shaped member aforesaid and keys therein being fitted around an edge of said stack and each of said keys having a tongue formation extended obliquely into the aforesaid edge of the stack, at least two of said tongues being oppositely inclined, and said channel-shaped member having

means at its ends engaging endwise portions of the said keys nearest the extremities of said edge and preventing longitudinal movement of the channel member on said edge.

15. Binding means for book signatures and pages, said means including a plurality of locking keys disposed along the binding edge of said signatures or pages and each having a tongue extended obliquely into said signatures or pages and one of said tongues being inclined in a direction opposite to another of the same, together with an elongated channel fitted onto said edge and the keys thereon and having its free edge portions bent for engagement with said keys to prevent movement of the same laterally out of the channel and also to prevent longitudinal movement of the latter relative to said keys and said signatures or pages.

16. A book including a stack of leaves, a channel-shaped backbone of elongated form fitted around an edge of said stack and having disposed therein a plurality of keys substantially channel-shaped in cross section, each of said keys having an oblique tongue extended into said edge of the stack and one of said tongues being inclined oppositely in an oblique sense to another one of said tongues, said backbone being provided with means along its free edge parts catching each of said keys against separation therefrom in a lateral sense, said means catching the keys being further operable to prevent longitudinal movement of the backbone relative to said keys in their assembled relation with the stack as aforesaid.

ROBERT ALONZO WILLIAMS. 35
